UNITED STATES PATENT OFFICE.

RUDOLPH CONRADER, OF ERIE, PENNSYLVANIA.

APPARATUS FOR ACTUATING LIQUIDS.

No. 821,339.

Specification of Letters Patent.

Patented May 22, 1906.

Application filed December 24, 1902. Serial No. 136,431.

To all whom it may concern:

Be it known that I, RUDOLPH CONRADER, a citizen of the United States, residing at Erie, in the county of Erie and State of Pennsylvania, have invented new and useful Improvements in Apparatuses for Actuating Liquids, of which the following is a specification.

This invention relates to apparatuses for actuating liquids; and it consists in certain improvements in the construction thereof, as will be hereinafter fully described, and pointed out in the claims.

The invention is peculiarly adapted for raising liquids from wells, and especially effective with oil-wells or wells in which the maintenance of a certain measure of liquids is desirable.

The invention is illustrated in the accompanying drawings as follows:

Figure 1 shows a section of the lower end of the pump-chamber on the lines 1 1 in Figs. 2 and 3. Fig. 2 shows a section on the line 2 2 in Fig. 1. Fig. 3 shows a section on the line 3 3 in Fig. 1. Fig. 4 is a section of a quarter of a portion of the pump-chamber on the lines 4 4 in Figs. 6, 7, 11, and 12. Fig. 5 is a similar view of a portion of the pump-chamber on the lines 5 5 in Figs. 6, 7, 11, and 12. Fig. 6 is a top view of the pump-chamber. Fig. 7 shows a section on the line 7 7 in Figs. 4, 5, and 10. Fig. 8 is a section on the lines 8 8 in Figs. 6, 7, 11, and 12. Fig. 9 is a section on the line 9 9 in Figs. 4, 5, and 8. Fig. 10 shows a section on the lines 10 10 in Figs. 6, 7, 11, and 12. Fig. 11 shows a section on the lines 11 11 in Figs. 4, 5, and 10. Fig. 12 shows a section on the line 12 12 in Figs. 4, 5, and 10. Fig. 13 shows a section of the parts above the pump-chamber on the lines 13 13 in Figs. 14 and 15. Fig. 14 shows a section on the line 14 14 in Fig. 13. Fig. 15 shows a section on the line 15 15 in Fig. 13. Fig. 16 shows a side elevation, partly in section, of the mechanism at the top of the well or end of the eduction-tube.

In the general operation of the apparatus liquid entering the pump-chamber ordinarily through the action of gravity puts in motion the mechanism for admitting to the pump-chamber above the liquid an actuating fluid, ordinarily air. In the preferred construction the air forces the liquid from the chamber by a following action of the air through the lift. Upon the arrival of the liquid at the end of the eduction-tube the air is cut off. The

pump does not operate again until a predetermined level of liquid is reached in the pump-chamber. This, as before stated, is particularly advantageous in oil-wells in that it will keep them at the desired level at all times.

A marks the pump-chamber. This is preferably formed of a piece of tubing of a length sufficient to form a column of liquid in the eduction-tube equal to what the air-pressure will readily handle. The liquid enters the perforated tube B'. This is secured to a bottom tube B, which is screwed onto the end of the chamber. The bottom plate is provided with a diaphragm B², on which is arranged the check-valves B³.

As the pump is being put in place or if there is any accident to the pump the pump-chamber will be subjected to the pressure of the accumulated liquid in the well. This accumulation sometimes amounts to several hundred feet. To obviate the effect of this in the chamber, I provide the following mechanism: A short joint C is secured in the tube forming the chamber A. This is provided with the lugs c. The diaphragm C' is secured to these lugs by means of the screws c'. The diaphragm is provided with the opening c², so that the pump-chamber at both sides of it are in communication. A pressure device, comprising the cylinder C² and piston C³, is mounted on the under side of the diaphragm C'. The upper end of the cylinder is in connection with the air-supply through the pipe C⁴, Figs. 1 and 7, and passage C¹¹. The under side of the cylinder is in communication with the upper end of the pump-chamber by means of a pipe C¹⁰. The stem C⁵ passes through the stuffing-box C⁶, through the plate B², and is secured to the valve C⁸. The valve C⁸ is arranged to control the inlet-passage C⁹. The gland C⁷ is mounted on the diaphragm B². The rod C⁵ passes through this gland. A spring C¹² presses the valve C⁸ to its seat. When the air is turned into the apparatus, it is carried through the pipe C⁴ to the upper end of the cylinder C². The piston C³ is of sufficient area to overcome the pressure on the valve C⁸ under any ordinary conditions. Immediately, therefore, the air is turned on the valve C⁸ is opened through the action of the pressure device. Liquid then enters the pump-chamber. Through the action of the apparatus hereinafter described the entering liquid turns the air into the pump-chamber.

105
110

As soon as the air in the pump-chamber balances the air passing through the pipe C⁴ the spring C¹², together with the pressure of the liquid outside the pump-chamber, closes the valve C⁸. This valve, as will be noted, acts more in the relation of a safety device rather than as a necessary feature of the pumping apparatus when the pump is working with the liquids at ordinary levels.

- 10 The liquid is forced out of the chamber through an eduction-tube D, and, as before stated, in the preferred construction the liquid is carried through the lift by a following action of the air through the lift. The operating mechanism in the pump-chamber is mounted on the under side of the top plate A'. (See Figs. 5, 6, 8, and 10.) The float F, which is initially actuated by the incoming liquid to effect the turning on of the air, is arranged in a contracted passage E⁵, the bottom of the passage being open. This passage communicates with the vent E², which is in communication with the eduction-tube through the passage E⁴. A valve E controls this passage. The valve operates upon the seat E' and is normally held away from its seat by means of the spring E³ and its gravity. The float is preferably formed of several tubes, as shown especially in Figs. 7 and 12. As the liquid rises in the pump-chamber it raises the float F. The mechanism hereinafter described turns the air into the chamber. The passage E⁵ and vent E² forming a free exit for the air, the level of the liquid in the passage E⁵ immediately rises, and so increases the effect of the liquid upon the float. As soon as the float is raised sufficiently to effect the purpose it contacts and closes the valve E. The eduction-tube D is of sufficient length below the connection E⁴ to cause sufficient friction to effect a pressure at the connection E⁴ less than that exerted upon the under side of the valve E. As a result the valve E remains on its seat until the liquid in the eduction-tube has passed by the connection E⁴, when the eduction-tube offering so much less frictional resistance to the air there is an immediate balancing effect on the valve E. The valve then opens, and the air following the liquid through the lift passes not only through the eduction-tube D, but through the passage E⁵. It will also be noted that these parts are then in position for the succeeding operation of the pump.
- 15 The main valve is actuated by a pressure device hereinafter described. The float F controls the passage which initially operates this pressure device, as follows: The lever f is pivoted at f'. (See Figs. 4, 8, and 9.) The pivot is supported by the yoke f², and the yoke is supported by the pipes f⁴ and f³. The pipe f³ is secured in a depending portion of the top A', containing the passage G². (See Figs. 8 and 10.) The chamber H is arranged 20 above the top A', which is in direct connec-

tion with the air-supply. The end of the lever f opposite that secured to the float F carries a rod G. This rod carries the valve-stem G', on which is arranged the valve g. The valve operates on the valve-seat g⁴ and controls the passage G². The valve-stem G' is arranged in the socket g' in the end of the rod G. A pin g² secures the valve-stem in the socket or preferably permits it to rotate therein. The valve-stem passes through the bushing g³.

25 The main valve I⁴ (see Figs. 5 and 10) is actuated by a pressure device comprising the chamber I and piston I'. The chamber I communicates with the passage G² by passage g⁵, these passages forming a by-pass from the chamber H. A stem I² communicates the action of the piston to the valve I⁴. The stem passes through the bushing I³. The valve I⁴ operates on the seat I⁵. The bushing I⁶ is screwed into the cap A' and carries the strainer I⁹. (See Figs. 5 and 6.) At the bottom of this bushing I⁶ is a spider i', having the passages i², which communicate with the valve-chamber I¹⁰. The valve I⁴ operates on the seat I⁶. Air passes through the opening I⁸ into the pump-chamber. The stem I² has the extension i, which passes through the spider i'. This forms a guide for the valve. The spring i² is arranged around the extension i and tends to force the valve I⁴ to its seat. An auxiliary passage I¹¹ extends from the passage G² to the chamber I¹⁰. A minute vent i⁴ extends through the piston I. This vent is relatively so much smaller than the passage g⁵ that substantially the initial pressure of the air is exerted on the piston. A passage i⁵ extends from the upper end of the chamber I to an exhaust-passage J. The exhaust-passage is formed in a depending portion of the casting A'. A pipe J' extends the exhaust up out of the pump-chamber and chamber H and preferably leads to the top of the well for purposes hereinafter described. The operation of this part of the mechanism is as follows: The air is turned into the chamber I through the action of the float on the valve g. This air-pressure immediately effects a movement of the piston I' and the opening of the valve I⁴. This turns the air into the pump-chamber and forces liquid therefrom through the eduction-tube. As soon as the level of the liquid in the chamber is lowered through this action the float of course goes with it, and this closes the valve g.

30 In order to continue the pressure in the chamber I after the closing of the valve g, I provide the following mechanism: A second passage K³ to the chamber I is arranged in a bushing K². The bushing K² is secured in the upper end of an extension K, which is screwed into the end of the depending branch of the top A', carrying the main-valve mechanism. The valve K' controls the passage 35

K^3 , and a passage K^4 connects the passage K^3 with the passage C^{11} . The passage C^{11} is in the casting depending from the top A' and extends into the chamber H and is therefore at all times in communication with the air-supply. The valve-stem k^2 of the valve K' is carried by the piston k' . This piston operates in a chamber k in the extension K . The spring k^6 normally holds the piston in its upward position and the valve K' to its seat. A passage k^3 extends from the upper end of the chamber k into a pipe k^4 , which extends to the upper end of the pump-chamber. As soon, therefore, as the air is turned into the pump-chamber air passes through the pipe k^4 and the passage k^3 and operating on the piston k' opens the valve K' . This puts the chamber I in communication with the air-supply through the passages K^3 , K^4 , and C^{11} , so that pressure is maintained in the chamber I after the closing of the valve g . This pressure is maintained until the liquid arrives at the end of the eduction-tube. If no mechanism is arranged at the end of the eduction-tube, the air will exhaust through the eduction-tube after the expulsion of a part of the liquid, so as to reduce the pressure in the pump-chamber. With this reduction of pressure the spring k^6 is of sufficient strength to move the piston k , and thus close the valve K' . Immediately upon the closing of the valve K' air exhausts from the chamber I through the vent i^4 and passage i^5 , and the main valve is closed through the action of the spring i^2 and the air-pressure upon it. In order to assure a marked reduction of the pressure in the chamber, as just described, I provide a reduced passage l' (see Fig. 13) of suitable length, so that the friction in that passage will be sufficiently great in comparison to the friction in the eduction-tube to effect the reduction in the pump-chamber. In order to adjust the spring k^6 so as to operate properly with different air-pressure, I provide the adjusting-screw k^7 . This has the shoulder k^8 , on which the spring rests, and the stem k^9 with the squared end, and this stem passes through the gland k^8 . With this means the spring may be adjusted so as to act, upon a reduction of pressure in the chamber and still not prevent the action of the piston k' with the initial pressure in the pump-chamber. It will also be noted that the spring may be adjusted so that a certain amount of expansion may be utilized—that is, it may be adjusted so as to act with a reduction in the pump-chamber incident to the reduction of pressure by the passage of a portion of the column of liquid from the eduction-tube.

I will summarize the operation of the device so far as described. The air being turned on operates upon the pressure device, comprising the chamber C^2 and piston C , (see Fig.

1,) to open the valve C^8 . Liquid then enters the chamber and rising to a sufficient level on the float lifts the float and opens the valve g . Air then passing from the passage G^2 to the chamber I operates upon the piston I' and opens the main valve. The air entering the chamber forces the liquid out of the eduction-tube, and as there is a vent through the passage E^2 the liquid rises in this passage and lifts the float F , thus closing the valve E to the vent. The float then drops back to the level of the liquid and eventually closes the valve g . Before this occurs, however, there is sufficient pressure in the chamber to operate the piston k' , the air passing to the chamber k through the pipes k^4 and passage k^3 . The piston k' operates the valve K' , and thus opens into the chamber I a passage from the air-supply by way of the passages C^{11} , K^4 , and K^3 . The main valve is therefore maintained in its open position until there is a balancing of the pressure on the piston I' . This may be accomplished, as heretofore described, by the closing of the valve K' and the escape of air through the vent i^4 , so that atmospheric pressure may be exerted on both sides of the piston, thus allowing the spring i^2 to close the main valve. The air as soon as it reaches a position in the eduction-tube opposite the connection E^4 will balance the pressure on the valve E , and thus permit the spring E^3 to open the valve. Immediately the air is turned onto the chamber it will be noted that the pressure on the piston C^3 is balanced through the action of air conveyed through the pipe C^{10} , thus permitting the closing of the valve C^8 by the spring C^{12} . This brings the parts to their initial position and the device is ready for a new operation. It will be noted that as the air-pressure is reduced in the chamber the pressure device will open the valve C^8 , so as to permit the entering of a fresh charge of liquid. The eduction-tube is screwed into a depending portion D' of the casting A' . An extension D^2 (see Fig. 13) is screwed into this casting from the upper side. The upper end of the extension D^2 fits in a sleeve a' , cast in the extension A^2 . This extension A^2 is secured on a collar or threaded bushing a . The bushing a is screwed into the tube forming the chamber A and against the tube A' . As the extension A^2 is being secured the bushing D^2 extends into the sleeve a' . A bushing D^3 is screwed into the extension D^2 , and the eduction-tube D^4 , which leads to the top, screwed into this. An air-pipe L surrounds the eduction-tube. One of the couplings L' of the air-pipe L is provided with the by-pass l . The lower end of the air-pipe is screwed into the sleeve a' and is closed by the extension D^2 . The by-pass l leads into the contracted pipe l' . The pipe l' leads into the chamber H . The pipe l' is of a size relative to the eduction-tube to cause sufficient

friction to reduce the pressure in the chamber after the expulsion of liquid in the eduction-tube for the purpose heretofore described.

I prefer to utilize the expansive force of the air to its fullest extent by cutting off the air immediately the top of the column of liquid reaches the top of the lift. If there is sufficient air-pressure to effect this result, then with the ordinary length of pipe the expansive force will be sufficient to expel the column of liquid, for the reason that as the air is expanded the column of liquid will grow less, and consequently require less pressure to expel it. I have provided a mechanism for accomplishing this, as follows: The end of the eduction-tube D^4 leads to a float-chamber N , and an outlet N^4 leads from the float-chamber. The float N' is arranged in the float-chamber. The stem n extends upwardly from the float through a gland N^2 , and the guide-stem n' extends down from the float through a gland N^3 . A valve mechanism M is supported by a bracket M' . It is connected by the pipe M^2 with the air-supply L^2 . It is also connected with the exhaust-pipe J' . The valve m controls a passage to the atmosphere leading from the exhaust-passage J' . A spring m' tends to close this valve. A valve m^2 controls a passage leading from the pipe M^2 , and the spring m^3 keeps this valve normally closed. A stem m^4 extends from the valve m and a stem m^5 from the valve m^2 . A bell-crank lever m^8 is carried by the bracket m^6 and is arranged to operate the stem m^4 . The bell-crank lever m^9 is carried by the bracket m^7 and is arranged to operate upon the stem m^5 . A spool n^3 is arranged upon the stem n and engages the lever m^8 to operate it. A similar spool n^2 operates upon the lever m^9 . It will be noted that the float-chamber N is inverted, so that the air acting upon the liquid in it will expel all the liquid from the float-chamber. Therefore after each operation the float N' will be in the bottom of the chamber. This will carry the bell-crank lever m^9 out of contact with the stem m^5 , and the bell-crank lever m^8 will be in position to effect the opening of the valve m , so that the exhaust-pipe J' will be in communication with the atmosphere. These parts remain in this position during the operation of the mechanism in the pump-chamber, as heretofore described, and remain in this position until the top of the column of liquid reaches the float-chamber. The float rises in the liquid, and this permits the valve m to close and forces open the valve m^2 through the operation of the bell-crank lever. This action connects the air-supply, through the pipe M^2 , valve m^2 , exhaust-pipe J' , exhaust-passage J , and passage i^5 , with the upper end of the chamber I , and thus effects an immediate balancing of pressure on the piston I' and the closing of the main valve. There is suffi-

cient expansive force in the air to complete the expulsion of the liquid.

It is preferable to have the bottom of the chamber k in communication with the exhaust-pipe both for taking care of any leakage through the piston and to prevent any compression of air in the chamber. The exhaust-passage J is extended by a pipe j . This connects the exhaust through the passage j' with the bottom of the chamber k . To prevent the accumulation of liquid through leakage or otherwise in the exhaust-passage, I provide an escape-valve j^3 at the bottom of the exhaust-passage j' . This valve is arranged in the valve-chamber j^2 and has double faces, one arranged to operate to close the passage j' and the other to close the outlet-passage j^4 . When air is turned into the chamber, it operates upon the valve j^3 and closes the passage j' . As soon as the pressure is turned onto the exhaust-passage or as soon as the pressure in the chamber is exhausted the valve drops back to the seat to close the passage j^4 . This permits the escape of liquid from the exhaust-passage to the chamber j^2 , and upon the next operation whatever accumulation there may be passes through the passage j^4 into the pump-chamber.

It will be noted that the pump is fully operative without the float and the valve g where the level of liquid entering the pump-chamber is such as to create pressure in the pump-chamber as it enters. Where this is the case, the air trapped in the chamber by the entering liquid will create sufficient pressure on the piston k' to actuate it and open the valve K' . Of course upon a reduction of the pressure in the chamber or the balancing of the pressure on the piston k' the operation would be the same as where the float mechanism is present. This mode of operation can be utilized where the pressure is quite slight by adjusting the spring k^6 so as to permit the action of the piston k' with such pressure.

It will be noted that should the liquid in the well through any cause rise in the eduction-tube to such a height that this column added to the column produced by the volume of liquid contained in the pump-chamber should be too great to be elevated by the air-pressure used the by-pass E^4 and its communicating passages will act as a relief, so that the liquid above this passage may be lifted separately from the balance of liquid in the chamber. If, for example, one-half the liquid in the pump-chamber has been forced into the eduction-tube by the air-pressure and at this point the column of liquid balances the air-pressure, the movement of liquid in the eduction-tube will cease, and with this cessation of movement the friction on the eduction-tube will also cease, so that

there will be a balancing of pressure on the valve E. The valve will then immediately open and the air will pass by this valve into the eduction-tube, cutting off the column at this point and elevating it, and on the next operation the liquid will be elevated from the chamber. It will also be noted that this is done automatically through the action of the fluid-pressure and through this action 10 carries out successive columns.

What I claim as new is—

1. In an apparatus for actuating liquids, the combination with a pump - chamber; means for admitting liquid to said chamber; 15 means for conveying liquid from said chamber; a connection between said chamber and a source of actuating-fluid supply; means controlled by the liquid entering the chamber for opening said connection; and means 20 acting independently of the liquid in said chamber for closing said connection.
2. In an apparatus for actuating liquids, the combination with a pump - chamber; means for admitting liquid to said chamber; 25 means for conveying liquid from said chamber, by a following action through the lift of an actuating fluid; a connection between said chamber and a source of actuating-fluid supply; means controlled by the liquid entering 30 the chamber for opening said connection; and means acting independently of the liquid in said chamber for closing said connection.
3. In an apparatus for actuating liquids, the combination with a pump - chamber; 35 means for admitting liquid to said chamber; means for conveying liquid from said chamber; a connection between said chamber and a source of actuating-fluid supply; means 40 controlled by the gravity of the liquid entering the chamber for opening said connection; and means acting independently of the liquid in said chamber for closing said connection.
4. In an apparatus for actuating liquids, the combination with a pump - chamber; 45 means for admitting liquid to said chamber; means for conveying liquid from said chamber, by a following action through the lift of an actuating fluid; a connection between said 50 chamber and a source of actuating-fluid supply; means controlled by the gravity of the liquid entering the chamber for opening said connection; and means acting independently of the liquid in said chamber for closing said connection.
5. In an apparatus for actuating liquids, the combination with a pump - chamber; means for admitting liquid to said chamber; 55 means for conveying liquid from said chamber; a connection between said chamber and a source of actuating - fluid supply; a float arranged in said chamber; means actuated by the float for effecting the opening of said connection; and means acting independently 60 of said float for closing said connection.

6. In an apparatus for actuating liquids, the combination with a pump - chamber; means for admitting liquid to said chamber; means for conveying liquid from said chamber by a following action through the lift of an actuating fluid; a connection between said chamber and a source of actuating-fluid supply; a float arranged in said chamber; means actuated by the float for effecting the opening of said connection; and means acting independently of said float for closing said connection. 75

7. In an apparatus for actuating liquids, the combination with a pump - chamber; means for admitting liquid to said chamber; 80 means for conveying liquid from said chamber; a connection between said chamber and a source of actuating-fluid supply; means controlled by the liquid entering the chamber for opening said connection; and means actuated at the arrival of the liquid forced from said chamber at a point remote from said chamber for closing said connection. 85

8. In an apparatus for actuating liquids, the combination with a pump - chamber; 90 means for admitting liquid to said chamber; means for conveying liquid from said chamber by a following action through the lift of an actuating fluid; a connection between said chamber and a source of actuating-fluid supply; means controlled by the liquid entering 95 the chamber for opening said connection; and means actuated at the arrival of the liquid forced from said chamber at a point remote from said chamber for closing said connection. 100

9. In an apparatus for actuating liquids, the combination with a pump - chamber; means for admitting liquid to said chamber; means for conveying liquid from said chamber; a connection between said chamber and a source of actuating-fluid supply; means controlled by the gravity of the liquid entering the chamber for opening said connection; and means actuated at the arrival of the liquid forced from said chamber at a point remote from said chamber for closing said connection. 105

10. In an apparatus for actuating liquids, the combination with a pump - chamber; 110 means for admitting liquid to said chamber; means for conveying liquid from said chamber; by a following action through the lift of an actuating fluid; a connection between said chamber and a source of actuating-fluid supply; means controlled by the gravity of the liquid entering the chamber for opening said connection; and means actuated at the arrival of the liquid forced from said chamber at a point remote from said chamber for closing said connection. 115

11. In an apparatus for actuating liquids, the combination with a pump - chamber; means for admitting liquid to said chamber; means for conveying liquid from said chamber. 120

ber; a connection between said chamber and a source of actuating-fluid supply; means controlled by the liquid entering the chamber for opening said connection; and means acting independently of the liquid in the chamber and at the arrival of the liquid forced from said chamber at a point remote from said chamber for closing said connection.

12. In an apparatus for actuating liquids,
10 the combination with a pump-chamber;
means for admitting liquid to said chamber;
means for conveying liquid from said chamber
15 by a following action through the lift of
an actuating fluid; a connection between
said chamber and a source of actuating-fluid
supply; means controlled by the liquid entering
the chamber for opening said connection;
and means acting independently of the liquid
20 in the chamber and at the arrival of the liquid
forced from said chamber at a point remote
from said chamber for closing said connection.

13. In an apparatus for acutating liquids, the combination with a pump-chamber; 25 means for admitting liquid to said chamber; means for conveying liquid from said chamber; a connection between said chamber and a source of actuating-fluid supply; means controlled by the gravity of the liquid entering the chamber for opening said connection; and means acting independently of the liquid 30 in the chamber and at the arrival of the liquid forced from said chamber at a point remote from said chamber for closing said connection.

35 *nection.*

14. In an apparatus for actuating liquids, the combination with a pump-chamber; means for admitting liquid to said chamber; means for conveying liquid from said chamber by a following action through the lift of an actuating fluid; a connection between said chamber and a source of actuating-fluid supply; means controlled by the gravity of the liquid entering the chamber for opening said connection; and means acting independently of the liquid in the chamber and at the arrival of the liquid forced from said chamber at a point remote from said chamber for closing said connection.

50 15. In an apparatus for actuating liquids, the combination with a pump - chamber; means for admitting liquid to said chamber; means for conveying liquid from said chamber; a connection between said chamber and
55 a source of actuating-fluid supply; a float in said chamber; means actuated by said float for effecting the opening of said connection; and means actuated at the arrival of the liquid forced from said chamber at a point re-
60 mote from said chamber for closing said connection.

16. In an apparatus for actuating liquids, the combination with a pump-chamber; means for admitting liquid to said chamber; means for conveying liquid from said chamber.

ber; by a following action through the lift of an actuating fluid; a connection between said chamber and a source of actuating-fluid supply; a float in said chamber; means actuated by said float for effecting the opening of said connection; and means actuated at the arrival of the liquid forced from said chamber at a point remote from said chamber for closing said connection.

17. In an apparatus for actuating liquids, 75
the combination with a pump - chamber;
means for admitting liquid to said chamber;
means for conveying liquid from said chamber;
a connection between said chamber and
a source of actuating-fluid supply; means controlled
by the liquid entering the chamber for
opening said connection; and means arranged
at said chamber and actuated by an equalizing
pressure thereon and independently of
the liquid in the chamber for closing said connection. 80
85

18. In an apparatus for actuating liquids, the combination with a pump - chamber; means for admitting liquid to said chamber; means for conveying liquid from said chamber; by a following action through the lift of an actuating fluid; a connection between said chamber and a source of actuating-fluid supply; means controlled by the liquid entering the chamber for opening said connection; and means arranged at said chamber and actuated by an equalizing pressure thereon and independently of the liquid in the chamber for closing said connection. 95

19. In an apparatus for actuating liquids, the combination with a pump-chamber; means for admitting liquid to said chamber; means for carrying liquid from said chamber; a connection between said chamber and a source of actuating-fluid supply; means controlled by the gravity of the liquid entering the chamber for opening said connection; and means arranged at said chamber and actuated by an equalizing pressure thereon and independently of the liquid in the chamber for closing said connection. 100 105 110

20. In an apparatus for actuating liquids, the combination with a pump-chamber; means for admitting liquid to said chamber; means for conveying liquid from said chamber; by a following action through the lift of an actuating fluid; a connection between said chamber and a source of actuating-fluid supply; means controlled by the gravity of the liquid entering the chamber for opening said connection; and means arranged at said chamber and actuated by an equalizing pressure thereon and independently of the liquid in the chamber for closing said connection. 115 120 125

21. In an apparatus for actuating liquids, the combination with a pump-chamber; means for admitting liquid to said chamber; means for conveying liquid from said chamber; a connection between said chamber and 130

a source of actuating-fluid supply; means controlled by the liquid entering the chamber for opening said connection; and means actuated by an equalizing pressure incident to the arrival of the liquid at a point remote from the chamber for closing said connection.

22. In an apparatus for actuating liquids, the combination with a pump - chamber; means for admitting liquid to said chamber; means for conveying liquid from said chamber; a connection between said chamber and a source of actuating-fluid supply; means controlled by the liquid entering the chamber for opening said connection; and means arranged at the chamber and actuated by an equalizing pressure incident to the arrival of the liquid at a point remote from the chamber for closing said connection.

23. In an apparatus for actuating liquids, the combination with a pump - chamber; means for admitting liquid to said chamber; means for conveying liquid from said chamber; a connection between said chamber and a source of actuating-fluid supply; means controlled by the gravity of the liquid entering the chamber for opening said connection; and means actuated by an equalizing pressure incident to the arrival of the liquid at a point remote from the chamber for closing said connection.

24. In an apparatus for actuating liquids, the combination with a pump - chamber; means for admitting liquid to said chamber; means for conveying liquid from said chamber; a connection between said chamber and a source of actuating-fluid supply; and mechanism comprising a pressure device actuated by fluid-pressure in the chamber for holding open said connection.

25. In an apparatus for actuating liquids, the combination with a pump - chamber; means for admitting liquid to said chamber; means for conveying liquid from said chamber, by a following action through the lift of an actuating fluid; a connection between said chamber and a source of actuating-fluid supply; and mechanism comprising a pressure device actuated by fluid - pressure in the chamber for holding open said connection.

26. In an apparatus for actuating liquids, the combination with a pump - chamber; means for admitting liquid to said chamber; means for conveying liquid from said chamber; a connection between said chamber and a source of actuating-fluid supply; mechanism comprising a pressure device actuated by fluid-pressure in the chamber for holding open said connection; and a connection between said pressure device and the top of the chamber whereby said pressure device may be actuated directly by actuating fluid.

27. In an apparatus for actuating liquids, the combination with a pump - chamber; means for admitting liquid to said chamber; means for conveying liquid from said chamber by a following action through the lift of

ber; a connection between said chamber and a source of actuating-fluid supply; mechanism comprising a pressure device actuated by fluid-pressure in the chamber for holding open said connection; and means acting independently of the liquid in the chamber for equalizing the pressure on said pressure device to effect the closing of said connection.

28. In an apparatus for actuating liquids, the combination with a pump - chamber; means for admitting liquid to said chamber; means for conveying liquid from said chamber; a connection between said chamber and a source of actuating-fluid supply; mechanism comprising a pressure device actuated by fluid-pressure in the chamber for holding open said connection; means acting at the arrival of the liquid at a point remote from the chamber for equalizing the pressure on said pressure device to effect the closing of said connection.

29. In an apparatus for actuating liquids, the combination with a pump - chamber; means for admitting liquid to said chamber; means for conveying liquid from said chamber; a connection between said chamber and a source of actuating-fluid supply; a valve controlling said connection; a pressure device controlling said valve; an auxiliary valve controlling the admission of actuating fluid to said pressure device; a motor controlling said auxiliary valve, said motor being arranged to be actuated by a fluid-pressure in the chamber during the expulsion of liquid.

30. In an apparatus for actuating liquids, the combination with a pump - chamber; means for admitting liquid to said chamber; means for conveying liquid from said chamber by the following action through the lift of the actuating fluid; a connection between said chamber and a source of actuating-fluid supply; a valve controlling said connection; a pressure device controlling said valve; an auxiliary valve controlling the admission of actuating fluid to said pressure device; and a motor controlling said auxiliary valve, said motor being arranged to be actuated by a fluid-pressure in the chamber during the expulsion of liquid.

31. In an apparatus for actuating liquids, the combination with a pump - chamber; means for admitting liquid to said chamber; means for conveying liquid from said chamber; a connection between said chamber and a source of actuating - fluid supply; means controlled by the liquid entering the chamber for opening said connection; mechanism actuated by fluid-pressure in the chamber for holding open said connection.

32. In an apparatus for actuating liquids, the combination with a pump - chamber; means for admitting liquid to said chamber; means for conveying liquid from said chamber by a following action through the lift of

an actuating fluid; a connection between said chamber and a source of actuating-fluid supply; means controlled by the liquid entering the chamber for opening said connection; mechanism actuated by fluid-pressure in the chamber for holding open said connection.

33. In an apparatus for actuating liquids, the combination with a pump-chamber; means for admitting liquid to said chamber; means for conveying liquid from said chamber; a connection between said chamber and a source of actuating-fluid supply; means controlled by gravity of the liquid entering the chamber for opening said connection; mechanism actuated by fluid-pressure in the chamber for holding open said connection.

34. In an apparatus for actuating liquids, the combination with a pump-chamber; means for admitting liquid to said chamber; means for conveying liquid from said chamber; a connection between said chamber and a source of actuating-fluid supply; means controlled by the liquid entering the chamber for opening said connection; mechanism actuated by fluid-pressure in the chamber for holding open said connection; and means for equalizing the pressure on said mechanism to close the connection.

35. In an apparatus for actuating liquids, the combination with a pump-chamber; means for admitting liquid to said chamber; means for conveying liquid from said chamber; a connection between said chamber and a source of actuating-fluid supply; means controlled by the liquid entering the chamber for opening said connection; mechanism actuated by fluid-pressure in the chamber for holding open said connection; and means acting independently of the liquid in the chamber for equalizing the pressure on said mechanism to close the connection.

36. In an apparatus for actuating liquids, the combination with a pump-chamber; means for admitting liquid to said chamber; means for conveying liquid from said chamber by a following action through the lift of an actuating fluid; a connection between said chamber and a source of actuating-fluid supply; means controlled by the liquid entering the chamber for opening said connection; mechanism actuated by fluid-pressure in the chamber for holding open said connection; and means acting independently of the liquid in the chamber for equalizing the pressure on said mechanism to close the connection.

37. In an apparatus for actuating liquids, the combination with a pump-chamber; means for admitting liquid to said chamber; means for conveying liquid from said chamber; a connection between said chamber and a source of actuating-fluid supply; means controlled by the gravity of the liquid entering the chamber for opening said connection; mechanism actuated by fluid-pressure in the chamber for holding open said connection;

and means acting independently of the liquid in the chamber for equalizing the pressure on said mechanism to close the connection.

38. In an apparatus for actuating liquids, the combination with a pump-chamber; means for admitting liquid to said chamber; means for conveying liquid from said chamber; a connection between said chamber and a source of actuating-fluid supply; means controlled by the liquid entering the chamber for opening said connection; mechanism actuated by fluid-pressure in the chamber for holding open said connection; and means actuated at the arrival of liquid at a point remote from the chamber for equalizing the pressure of said mechanism to close the connection.

39. In an apparatus for actuating liquids, the combination with a pump-chamber; means for admitting liquid to said chamber; means for conveying liquid from said chamber; a connection between said chamber and a source of actuating-fluid supply; means controlled by the gravity of the liquid entering the chamber for opening said connection; mechanism actuated by fluid-pressure in the chamber for holding open said connection; and means actuated at the arrival of liquid at a point remote from the chamber for equalizing the pressure of said mechanism to close the connection.

40. In an apparatus for actuating liquids, the combination with a pump-chamber; means for admitting liquid to said chamber; means for conveying liquids from said chamber; a connection between said chamber and an actuating-fluid supply; a pressure-actuated device controlling the admission of actuating fluid from said connection; a by-pass between said connection and said device; mechanism actuated by the entrance of liquid to said chamber for opening said by-pass; and means for maintaining communication between said connection and device after the closing of said by-pass.

41. In an apparatus for actuating liquids, the combination with a pump-chamber; means for admitting liquid to said chamber; means for conveying liquids from said chamber; a connection between said chamber and an actuating-fluid supply; a pressure-actuated device controlling the admission of actuating fluid from said connection; a by-pass between said connection and said device; mechanism actuated by the entrance of liquid to said chamber for opening said by-pass; and means actuated by pressure in the chamber for connecting said connection and device.

42. In an apparatus for actuating liquids, the combination with a pump-chamber; means for admitting liquid to said chamber; means for conveying liquids from said chamber by a following action through the lift of an actuating fluid; a connection between said

chamber and an actuating-fluid supply; a pressure-actuated device controlling the admission of actuating fluid from said connection; a by-pass between said connection and said device; mechanism actuated by the entrance of liquid to said chamber for opening said by-pass; and means actuated by pressure in the chamber for connecting said connection and device.

43. In an apparatus for actuating liquids, the combination with a pump-chamber; means for admitting liquid to said chamber; means for conveying liquids from said chamber; a connection between said chamber and an actuating-fluid supply; a pressure-actuated device controlling the admission of actuating fluid from said connection; a by-pass between said connection and said device; mechanism actuated by the entrance of liquid to said chamber for opening said by-pass; and means actuated by pressure in the chamber for maintaining communication between said connection and device after the closing of said by-pass.

44. In an apparatus for actuating liquids, the combination with a pump-chamber; means for admitting liquid to said chamber; means for conveying liquids from said chamber by a following action through the lift of an actuating fluid; a connection between said chamber and an actuating-fluid supply; a pressure-actuated device controlling the admission of actuating fluid from said connection; a by-pass between said connection and said device; mechanism actuated by the entrance of liquid to said chamber for opening said by-pass; and means actuated by pressure in the chamber for maintaining communication between said connection and device after the closing of said by-pass.

45. In an apparatus for actuating liquids, the combination with a pump-chamber; means for admitting liquid to said chamber; means for conveying liquids from said chamber; a connection between said chamber and an actuating-fluid supply; a pressure-actuated device controlling the admission of actuating fluid from said connection; a by-pass between said connection and said device; a float arranged in said chamber; mechanism actuated by said float for controlling said by-pass; and means for maintaining communication between said connection and device after the closing of said by-pass.

46. In an apparatus for actuating liquids, the combination with a pump-chamber; means for admitting liquid to said chamber; means for conveying liquids from said chamber; a connection between said chamber and an actuating-fluid supply; a pressure-actuated device controlling the admission of actuating fluid from said connection; a by-pass between said connection and said device; mechanism actuated by the entrance of liquid to said chamber for opening said by-pass; and means

for maintaining communication between said connection and device after the closing of said by-pass; and means for balancing the pressure on said device to close said connection.

47. In an apparatus for actuating liquids, the combination with a pump-chamber; means for admitting liquid to said chamber; means for conveying liquids from said chamber; a connection between said chamber and actuating-fluid supply; a pressure-actuated device controlling the admission of actuating fluid from said connection; a by-pass between said connection and said device; mechanism actuated by the entrance of liquid to said chamber for opening said by-pass; and means for maintaining communication between said connection and device after the closing of said by-pass; and means acting independently of the liquid in the chamber for balancing the pressure on said device to close the connection.

48. In an apparatus for actuating liquid the combination with a pump-chamber; means for admitting liquid to said chamber; means for conveying liquids from said chamber; a connection between said chamber and an actuating-fluid supply; a main valve controlling said connection; a pressure-actuated device controlling said main valve; a by-pass between said connection and said pressure device; an auxiliary valve controlling said by-pass; mechanism for actuating said auxiliary valve; and a second auxiliary valve controlling the admission of actuating fluids to said pressure device; and means for maintaining said second auxiliary valve in its open position after the closing of the first auxiliary valve.

49. In an apparatus for actuating liquid the combination with a pump-chamber; means for admitting liquid to said chamber; means for conveying liquids from said chamber; a connection between said chamber and an actuating-fluid supply; a main valve controlling said connection; a pressure-actuated device controlling said main valve; a by-pass between said connection and said pressure device; an auxiliary valve controlling said by-pass; mechanism for actuating said auxiliary valve; a second auxiliary valve controlling the admission of actuating fluids to said pressure device a second pressure device controlling said second auxiliary valve; and a connection between said second pressure device and the pump-chamber.

50. In an apparatus for actuating liquid the combination with a pump-chamber; means for admitting liquid to said chamber; means for conveying liquids from said chamber by a following action through the lift of an actuating fluid; a connection between said chamber and an actuating-fluid supply; a main valve controlling said connection; a pressure-actuated device controlling said

main valve; a by-pass between said connection and said pressure device; an auxiliary valve controlling said by-pass; mechanism for actuating said auxiliary valve; a second auxiliary valve controlling the admission of actuating fluids to said pressure device; a second pressure device controlling said second auxiliary valve; and a connection between said second pressure device and the pump-chamber.

51. In an apparatus for actuating liquid the combination with a pump-chamber; means for admitting liquid to said chamber; means for conveying liquids from said chamber; a connection between said chamber and an actuating-fluid supply; a main valve controlling said connection; a pressure-actuated device controlling said main valve; a by-pass between said connection and said pressure device; an auxiliary valve controlling said by-pass; mechanism for actuating said auxiliary valve; a second auxiliary valve controlling a passage from said connection to said pressure device; a second pressure device controlling said second auxiliary valve; a connection between said pressure device and the pump-chamber; and means for closing said second auxiliary valve upon reduction of pressure in the chamber.

52. In an apparatus for actuating liquid the combination with a pump-chamber; means for admitting liquid to said chamber; means for conveying liquids from said chamber; a connection between said chamber and an actuating-fluid supply; a main valve controlling said connection; a pressure-actuated device controlling said main valve; a by-pass between said connection and said pressure device; an auxiliary valve controlling said by-pass; a float in said chamber; means acting with said float for controlling said auxiliary connection and device for the closing of said auxiliary valve.

53. In an apparatus for actuating liquid the combination with a pump-chamber; means for admitting liquid to said chamber; means for conveying liquids from said chamber; a connection between said chamber and an actuating-fluid supply; a main valve controlling said connection; a pressure-actuated device controlling said main valve; a by-pass between said connection and said pressure device; an auxiliary valve controlling said by-pass; a float in said chamber; means acting with said float for controlling said auxiliary valve; means for maintaining communication between said connection and device after the closing of said auxiliary valve; and means actuated at the arrival of the liquid at a point remote from the chamber for equalizing the pressure on said pressure device to admit the closing of said main valve.

54. In an apparatus for actuating liquid the combination with a pump-chamber; means for admitting liquid to said chamber;

means for conveying liquid from said chamber; a connection between said chamber and an actuating-fluid supply; a main valve controlling said connection; a pressure-actuated device controlling said main valve; a by-pass between said connection and said pressure device; an auxiliary valve controlling said by-pass; a float in said chamber; means acting with said float for controlling said auxiliary valve; and means for maintaining communication between said connection and device after the closing of said auxiliary valve; and means acting independently of the liquid in the chamber controlling said pressure device to close the main valve.

55. In an apparatus for actuating liquid the combination with a pump-chamber; means for admitting liquid to said chamber; means for conveying liquid from said chamber by a following action through the lift of an actuating fluid; a connection between said chamber and an actuating-fluid supply; a main valve controlling said connection; a pressure-actuated device controlling said main valve; a by-pass between said connection and said pressure device; an auxiliary valve controlling said by-pass; a float in said chamber; means acting with said float for controlling said auxiliary valve; and means for maintaining communication between said connection and device after the closing of said auxiliary valve; and means acting independently of the liquid in the chamber controlling said pressure device to close the main valve.

56. In an apparatus for actuating liquid the combination with a pump-chamber; means for admitting liquid to said chamber; means for conveying liquids from said chamber; a connection between said chamber and an actuating-fluid supply; a main valve controlling said connection; a pressure-actuated device controlling said main valve; a by-pass between said connection and said pressure device; the valve *g* controlling said by-pass; the stem *G* extending from said valve; the rod *G* extending to the lever *f* carried in the chamber; and the float *F* arranged to operate upon the lever *f*.

57. In an apparatus for actuating liquids, the combination with the pump-chamber; means for admitting liquid to said chamber; means for conveying liquid from said chamber; a connection between said chamber and an actuating-fluid supply; the valve *I* controlling said connection; a pressure device comprising the chamber *I*, the piston *I'* controlling said valve; a by-pass to the chamber *I*; an auxiliary valve controlling said by-pass; means actuated by the entering liquid for controlling said auxiliary valve; and means acting independently of the liquid in the chamber for balancing the pressure on the pressure device to effect the closing of the valve *I*.

58. In an apparatus for actuating liquids, the combination with the pump-chamber; means for admitting liquid to said chamber; means for conveying liquid from said chamber; a connection between said chamber and an actuating-fluid supply; the valve I^4 controlling said connection; a pressure device comprising the chamber I , the piston I' , controlling said valve, said piston being provided with a vent i^4 and the chamber with an exhaust-passage i^5 .

59. In an apparatus for actuating liquids, the combination of a pump-chamber; means for admitting liquid to said chamber; means for conveying liquid from said chamber; a connection between said chamber and an actuating-fluid supply; a pressure-actuated device controlling the admission of actuated fluid from said connection; the valve K' for controlling the admission of fluid to said pressure device; an auxiliary pressure device controlling said valve K ; a connection between said pressure device and the pump-chamber; and means for acting upon the pressure device for closing the valve K' upon a reduction of pressure in the chamber.

60. In an apparatus for actuating liquids, the combination of a pump-chamber; means for admitting liquid to such chamber; means for conveying liquid from said chamber by a following action through the lift of an actuating fluid; a connection between said chamber and an actuating-fluid supply; a pressure-actuated device controlling the admission of actuated fluid from said connection; the valve K' for controlling the admission of fluid to said pressure device; an auxiliary pressure device controlling said valve K ; a connection between said pressure device and the pump-chamber; and means for acting upon the pressure device for closing the valve K' upon a reduction of pressure in the chamber.

61. In an apparatus for actuating liquids, the combination of a pump-chamber; means for admitting liquid to said chamber; means for conveying liquid from said chamber; a connection between said chamber and an actuating-fluid supply; a pressure-actuated device controlling the admission of actuating fluid from said connection; the valve K' for controlling the admission of fluid to said pressure device; an auxiliary pressure device controlling said valve K' ; a connection between said pressure device and the pump-chamber; a spring k^6 acting upon said pressure device; means for adjusting the tension of said spring; and means for acting upon the pressure device for closing the valve K' upon a reduction of pressure in the chamber.

62. In an apparatus for actuating liquids, the combination with a pump-chamber; means for admitting liquid to said chamber; means for conveying liquids from said chamber; a connection between said chamber and

an actuating-fluid supply; the valve I^4 controlling said connection; pressure device comprising the chamber I and piston I' for actuating said valve; a by-pass leading to said pressure device; the valve g controlling said by-pass; means actuated by the entering liquid for actuating the valve g ; the valve K' controlling a connection for supplying actuating fluid to the chamber I ; a pressure device comprising the chamber k and piston k' ; a connection between the chamber k and the pump-chamber.

63. In an apparatus for actuating liquids, the combination with a pump-chamber formed of tubing; a fitting A' secured in said tubing forming a top for said chamber, said fitting carrying the valve mechanism controlling the action of the pump; and the chamber II arranged above said fitting and forming a part of the actuating-fluid-supply connection.

64. In an apparatus for actuating liquids, the combination of a pump-chamber; means for admitting liquid to said chamber; means for conveying liquid from said chamber; a connection between said chamber and a source of actuating-fluid supply; the valve I^4 controlling said connection; the chamber I ; the piston I' arranged in said chamber; the stem I^2 connecting said piston with the valve I^4 ; the by-pass G^2 ; the valve g controlling said by-pass; connection g^5 between said by-pass and the chamber I ; means actuated by the entering liquid for operating the valve g ; the valve K' ; a by-pass C^1 ; passage K^4 leading to said valve; a passage K^3 leading from said valve to the chamber I ; the chamber k ; the piston k' therein; the passage k^3 ; pipe k^4 in the upper end of the chamber.

65. In an apparatus for actuating liquids, the combination of a pump-chamber; means for admitting liquid to said chamber; means for conveying liquid from said chamber; a connection between said chamber and a source of actuating-fluid supply; the valve I^4 controlling said connection; the chamber I ; the piston I' arranged in said chamber; the stem I^2 connecting said piston with the valve I^4 ; the by-pass G^2 ; the valve g controlling said by-pass; connection g^5 between said by-pass and the chamber I ; means actuated by the entering liquid for operating the valve g ; the valve K' ; a by-pass C^1 ; passage K^4 leading to said valve, and a passage K^3 leading from said valve to the chamber I ; the chamber k ; the piston k' therein; the passage k^3 ; passage k^4 in the upper end of the chamber; the spring k^6 arranged against the piston k' and the adjusting-stud k^7 .

66. In an apparatus for actuating liquids, the combination with a pump-chamber; means for admitting liquid to said chamber; means for conveying liquid from said chamber; a connection between said chamber and an actuating-fluid supply; a pressure-actu- 135

ated device controlling the admission of actuated fluids to said chamber; and means actuated with the pressure in said chamber for controlling the pressure device.

5 67. In an apparatus for actuating liquids, the combination with a pump-chamber; means for admitting liquid to said chamber; means for conveying liquid from said chamber; a connection between said chamber and an actuating-fluid supply; a pressure-actuated device controlling the admission of actuated fluids to said chamber; means actuated with the pressure in said chamber for controlling the pressure device; a mechanism for adjusting said means to affect a closing at a desired pressure in the chamber.

68. In an apparatus for actuating liquids the combination with a pump-chamber; means for admitting liquid to said chamber; 20 means for conveying liquid from said chamber; a connection between said chamber and a source of actuating-fluid supply; means for conveying energy supplied from a source independent of the liquid and from a point 25 remote from said chamber to said connection at the chamber; means controlled by the energy so conveyed for closing said connection; and means actuated by the fluid forced from said chamber for controlling the energy conveyed.

69. In an apparatus for actuating liquids the combination with a pump-chamber; means for admitting liquid to said chamber; means for conveying liquid from said chamber by a following action through the lift of an actuating fluid; a connection between said chamber and a source of actuating-fluid supply; means for conveying energy supplied from a source independent of the liquid and 35 from a point remote from said chamber to said connection; means controlled by the energy so conveyed for closing said connection and means actuated by the fluid forced from said chamber for controlling the energy conveyed.

70. In an apparatus for actuating liquids the combination with a pump-chamber; means for admitting liquid to said chamber; means for conveying liquid from said chamber by a following action through the lift of an actuating fluid; a connection between said chamber and a source of actuating-fluid supply; means for conveying energy supplied from a source independent of the liquid and 45 from a point remote from said chamber to said connection at the chamber; means controlled by the energy so conveyed for closing said connection; and means actuated by the fluid forced from said chamber for controlling the energy conveyed.

71. In an apparatus for actuating liquids the combination with a pump-chamber; means for admitting liquid to said chamber; means for conveying liquid from said chamber; a connection between said chamber and

a source of actuating-fluid supply; means for conveying energy from a point remote from said chamber to said connection; means controlled by the energy so conveyed for closing said connection; means actuated by the fluid forced from said chamber for controlling the energy conveyed; and means controlled by the liquid entering the chamber for opening said connection. 70

72. In an apparatus for actuating liquids the combination with a pump-chamber; means for admitting liquid to said chamber; means for conveying liquid from said chamber by a following action through the lift of an actuating fluid; a connection between said chamber and a source of actuating-fluid supply; means for conveying energy from a point remote from said chamber to said connection; means controlled by the energy so conveyed for closing said connection; means actuated by the fluid forced from said chamber for controlling the energy conveyed; and means controlled by the liquid entering the chamber for opening said connection. 75

73. In an apparatus for actuating liquids the combination with a pump-chamber; means for admitting liquid to said chamber; means for conveying liquid from said chamber; a connection between said chamber and a source of actuating-fluid supply; means for conveying energy from a point remote from said chamber to said connection; means controlled by the energy so conveyed for closing said connection; means actuated by the fluid forced from said chamber for controlling the energy conveyed; and means controlled by the gravity of the liquid entering the chamber for opening said connection. 85

74. In an apparatus for actuating liquids the combination with a pump-chamber; means for admitting liquid to said chamber; means for conveying liquid from said chamber by a following action through the lift of an actuating fluid; a connection between said chamber and a source of actuating-fluid supply; means for conveying energy from a point remote from said chamber to said connection; means controlled by the energy so conveyed for closing said connection; means actuated by the fluid forced from said chamber for controlling the energy conveyed; and means controlled by the gravity of the liquid entering the chamber for opening said connection. 90

75. In an apparatus for actuating liquids, the combination with a pump-chamber; means for admitting liquid to said chamber; means for conveying liquid from said chamber; a connection between said chamber and a source of actuating-fluid supply; mechanism for closing said connection; a duct for conveying actuating fluid to said mechanism from a point remote from the chamber; means actuated by the fluid forced from said chamber controlling said duct; and means 105

115

125

130

controlled by the liquid entering the chamber for opening said connection.

76. In an apparatus for actuating liquids, the combination with a pump-chamber; 5 means for admitting liquid to said chamber; means for conveying liquid from said chamber; a connection between said chamber and a source of actuating-fluid supply; mechanism for closing said connection; a duct for 10 conveying actuating fluid to said mechanism from a point remote from the chamber; means actuated by the fluid forced from said chamber controlling said duct; and means controlled by the gravity of the liquid entering 15 the chamber for opening said connection.

77. In an apparatus for actuating liquids, the combination with a pump-chamber; means for admitting liquid to said chamber; 20 means for conveying liquid from said chamber; a connection between said chamber and a source of actuating-fluid supply; means controlled by the liquid entering the chamber for opening said connection; mechanism arranged at the chamber and actuated 25 by an equalizing of pressure on the mechanism for closing said connection; a duct leading from a point remote from said chamber to said mechanism, the duct being arranged to convey actuating fluid to equalize the 30 pressure on said mechanism; and means controlling said duct.

78. In an apparatus for actuating liquids, the combination with a pump-chamber; means for admitting liquid to said chamber; 35 means for conveying liquid from said chamber by a following action through the lift of an actuating fluid; a connection between said chamber and a source of actuating-fluid supply; means controlled by the liquid entering 40 the chamber for opening said connection; mechanism arranged at the chamber and actuated by an equalizing of pressure on the mechanism for closing said connection; a duct leading from a point remote from said 45 chamber to said mechanism, the duct being arranged to convey actuating fluid to equalize the pressure on said mechanism; and means controlling said duct.

79. In an apparatus for actuating liquids, the combination with a pump-chamber; 50 means for admitting liquid to said chamber; means for conveying liquid from said chamber; a connection between said chamber and a source of actuating-fluid supply; means actuated by pressure in the chamber maintaining 55 said connection in an open position; mechanism arranged at the chamber and actuated by an equalizing of pressure on the mechanism for closing said connection; a duct leading from a point remote from said chamber to said mechanism, the duct being arranged to convey actuating fluid to equalize the pressure on said mechanism; and means controlling said duct.

80. In an apparatus for actuating liquids,

the combination with a pump-chamber; means for admitting liquid to said chamber; means for conveying liquid from said chamber by a following action through the lift of an actuating fluid; a connection between 70 said chamber and a source of actuating-fluid supply; means actuated by pressure in the chamber maintaining said connection in an open position; mechanism arranged at the chamber and actuated by an equalizing of 75 pressure on the mechanism for closing said connection; a duct leading from a point remote from said chamber to said mechanism, the duct being arranged to convey actuating fluid to equalize the pressure on said mechanism; and means controlling said duct.

81. In an apparatus for actuating liquids, the combination with a pump-chamber; means for admitting liquid to said chamber; 80 means for conveying liquid from said chamber; a connection between said chamber and a source of actuating-fluid supply; means controlled by the liquid entering the chamber for opening said connection; mechanism arranged at the chamber and actuated by an 85 equalizing pressure for closing said connection; a duct leading from a point remote from said chamber to said mechanism, the duct being arranged to convey actuating fluid to equalize the pressure on said mechanism; means controlling said duct; and means actuated by liquid forced from said chamber for controlling said duct.

82. In an apparatus for actuating liquids, the combination with a pump-chamber; 90 means for admitting liquid to said chamber; means for conveying liquid from said chamber; a connection between said chamber and a source of actuating-fluid supply; means controlled by the gravity of the liquid entering 95 the chamber for opening said connection; mechanism arranged at the chamber and actuated by an equalizing pressure for closing said connection; a duct leading from a point remote from said chamber to said mechanism, the duct being arranged to convey actuating fluid to equalize the pressure on said mechanism; means controlling said duct; and means actuated by liquid forced from said chamber for controlling said duct.

83. In an apparatus for actuating liquids, the combination with a pump-chamber; means for admitting liquid to said chamber; 100 means for conveying liquids from said chamber; a connection between said chamber and an actuating-fluid supply; a pressure-actuated device controlling the admission of actuating fluid from said connection; a by-pass between said connection and said device; mechanism actuated by the entrance of liquid to said chamber for opening said by-pass; 110 means for maintaining communication between said connection and device after the closing of said by-pass; a duct leading from a point remote from said chamber to said device.

vice, said duct being arranged to convey actuating fluid to said device and deliver it to said device to balance the pressure thereon; and means for controlling said duct.

5 84. In an apparatus for actuating liquids, the combination with a pump-chamber; means for admitting liquid to said chamber; means for conveying liquids from said chamber; a connection between said chamber and an actuating-fluid supply; a pressure-actuated device controlling the admission of actuating fluid from said connection; a by-pass between said actuating fluid from said connection; a by-pass between said connection and said device; mechanism actuated by the entrance of liquid to said chamber for opening said by-pass; means for maintaining communication between said connection and device after the closing of said by-pass; a duct leading from a point remote from said chamber to said device, said duct being arranged to convey actuating fluid to said device and deliver it to said device to balance the pressure thereon; and means actuated by the liquid forced from the chamber for controlling said duct.

30 85. In an apparatus for actuating liquids the combination with a pump-chamber; means for admitting liquid to said chamber; means for conveying liquid from said chamber; a connection between said chamber and a source of actuating-fluid supply; means for conveying energy supplied from a source independent of the actuated liquid from a point remote from said chamber to said connection; means controlled by the energy so conveyed for closing said connection; the float-chamber N; means for conveying fluid from said chamber; the float N' in said float-chamber; and means controlled by said float for controlling said energy.

45 86. In an apparatus for actuating liquids, the combination with a pump-chamber; means for admitting liquid to said chamber; means for conveying liquid from said chamber; a connection between said chamber and a source of actuating-fluid supply; mechanism for closing said connection; a duct for conveying actuating fluid to said mechanism from a point remote from the chamber; the float-chamber N arranged in the means for conveying liquid from the chamber; the float N' and means actuated by said float for controlling said duct.

55 87. In an apparatus for actuating liquids, the combination with a pump-chamber; means for admitting liquid to said chamber; means for conveying liquid from said chamber; a connection between said chamber and a source of actuating-fluid supply; mechanism for closing said connection; a duct forming an exhaust-passage and a passage for conveying actuating fluid to said mechanism; the valve M comprising the valve m opening to the atmosphere; the valve m' opening to a

source of actuating-fluid supply; the bell-crank lever m^o for actuating said valves respectively; the float-chamber N and float N' arranged to actuate said bell-crank levers.

70 88. In an apparatus for actuating liquids, the combination with a pump-chamber; means for admitting liquid to said chamber; means for conveying liquid from said chamber; a connection between said chamber and an actuating-fluid supply; a valve controlling said connection; means for conveying actuating fluid to said pressure device to open the valve; a duct from said pressure device to a point remote from the chamber; and from the opposite part of the pressure device from that on which pressure is exerted, said duct forming initially an exhaust-passage; means for turning an actuating fluid into said duct to affect a counter-pressure on said pressure device to close the valve.

80 89. In an apparatus for actuating liquids, the combination with a pump-chamber; means for admitting liquid to said chamber; means for conveying liquid from said chamber; a connection between said chamber and an actuating-fluid supply; a valve controlling said connection; a pressure device controlling said valve; the valve K' controlling a connection to said pressure device; a pressure-actuated motor controlling said valve K'; a duct leading from the opposite side of the motor to which pressure is admitted; and means for turning in an actuating fluid for balancing said pressure device and motor to affect the closing of said valves.

90 90. In an apparatus for actuating liquids, the combination with a pump-chamber; means for admitting liquid to said chamber; means for conveying liquid from said chamber by a following action through the lift of an actuating fluid; a connection between said chamber and an actuating-fluid supply; a valve controlling said connection; a pressure device controlling said valve; the valve K' controlling a connection to said pressure device; a pressure-actuated motor controlling said valve K'; a duct leading from the opposite side of the motor to which pressure is admitted; and means for turning in an actuating fluid for balancing said pressure device and motor to effect the closing of said valves.

100 91. In an apparatus for actuating liquids, the combination with a pump-chamber; means for admitting liquid to said chamber; means for conveying liquid from said chamber; a valve controlling said connection; a pressure device controlling said valve; a passage leading from said pressure device to a point remote from the chamber; the chamber j² at the bottom of said passage and valve j³ arranged in said chamber for the purpose described.

110 92. In an apparatus for actuating liquids, the combination with a pump-chamber; means for admitting liquid to said chamber;

means for conveying liquid from said chamber; a valve controlling said connection; a pressure device controlling said valve; a passage conveying actuating fluid to said pressure device; a second valve controlling said passage; means actuated by the entering liquid for controlling said second valve; a pressure-actuated device for opening a second passage leading to said pressure device; a third valve controlling said second passage; a fluid-actuated motor controlling said valve; a duct from said pressure device and said motor forming initially an exhaust-passage therefor; and means for turning in an actuating fluid for balancing said pressure device and motor for closing the valves controlled by them.

93. In an apparatus for actuating liquids, the combination with a pump-chamber; means for admitting liquid to said chamber; means for conveying liquid from said chamber by a following action through the lift of an actuating fluid; a valve controlling said connection; a pressure device controlling said valve; a passage conveying actuating fluid to said pressure device; a second valve controlling said passage; means actuated by the entering liquid for controlling said second valve; a pressure-actuated device for opening a second passage leading to said pressure device; a third valve controlling said second passage; a fluid-actuated motor controlling said valve; a duct from said pressure device and said motor forming initially an exhaust-passage therefor; and means for turning in an actuating fluid for balancing said pressure device and motor for closing the valves controlled by them.

94. In an apparatus for actuating liquid, the combination with a chamber; a connection leading to said chamber from a supply of actuating fluid; a float in said chamber; an inlet to said chamber; a valve for closing said inlet; and means actuated by the actuating fluid for opening said valve.

95. In an apparatus for actuating liquid, the combination of a chamber; a connection leading to said chamber from a supply of actuating fluid; a float in said chamber; an inlet to said chamber; a valve for closing said inlet; and means actuated by the actuating fluid for opening said valve; and means for closing said valve before excessive pressure is exerted in the chamber by the liquid.

96. In an apparatus for actuating liquid, the combination of a chamber; a connection leading to said chamber from a supply of actuating fluid; means for conveying fluid from said chamber by a following action through the lift of an actuating fluid; a float in said chamber; an inlet to said chamber; a valve for closing said inlet; and means actuated by the actuating fluid for opening said valve; and means for closing said valve be-

fore excessive pressure is exerted in the chamber by the liquid.

97. In an apparatus for actuating liquid, the combination of a chamber; a connection leading to said chamber from a supply of actuating fluid; a float in said chamber; an inlet to said chamber; a valve for closing said inlet; a pressure device controlling said valve, said pressure device being arranged to have the actuating fluid turned into it as the actuating fluid is turned into the apparatus; and means for balancing said pressure device to permit the closing of the valve, the actuation of said balancing means being effected by the entering liquid.

98. In an apparatus for actuating liquid, the combination of a chamber; a connection leading to said chamber from a supply of actuating fluid; a float in said chamber; an inlet to said chamber; a valve for closing said inlet; a pressure device controlling said valve comprising the chamber C², piston C³, connection C⁴ to a source of motor-fluid supply; and the connection C¹⁰ with the chamber.

99. In an apparatus for actuating liquids the combination of a chamber; a connection between said chamber and a source of actuating-fluid supply; means actuated by the entering liquid for opening said connection; a valve controlling the entrance of liquid; a pressure device controlling said valve, the side of the pressure device opening said valve being connected with the source of actuating-fluid supply; and a connection between the opposite side of said pressure device and the chamber.

100. In an apparatus for actuating liquids the combination of a chamber; a connection between said chamber and a source of actuating-fluid supply; means actuated by the entering liquid for opening said connection; a valve controlling the entrance of liquid; a pressure device controlling said valve, the side of the pressure device opening said valve being connected with the source of actuating-fluid supply; a connection between the opposite side of said pressure device and the chamber; and means for cutting off the connection between the chamber and actuating-fluid supply and for exhausting the pressure in the chamber.

101. In an apparatus for actuating liquids, the combination of a chamber; a connection between said chamber and a source of actuating-fluid supply; means actuated by the entering liquid for opening said connection; a valve controlling the entrance of liquid; a pressure device controlling said valve, the side of the pressure device opening said valve being connected with the source of actuating-fluid supply, and a connection between the opposite side of said pressure device and the chamber; the check-valves B³ for preventing an outflow of liquid from the chamber.

102. In an apparatus for actuating liquids, the combination of a pump-chamber; an eduction-tube; a connection between the chamber and a source of actuating fluid; a 5 float in said chamber; a passage in which said float is arranged, said passage being open at the bottom; a vent for said passage; and means controlled by said float for opening said connection. 70
103. In an apparatus for actuating liquids, the combination of a pump-chamber; an eduction-tube; means for conveying liquid through said tube by a following action through the lift of an actuating fluid; a 10 connection between the chamber and a source of actuating fluid; a float in said chamber; a passage in which said float is arranged, said passage being open at the bottom; a vent for said passage; and means controlled by said 15 float for opening said connection. 75
104. In an apparatus for actuating liquids, the combination of a pump-chamber; an eduction-tube; a connection between the chamber and a source of actuating fluid; a 15 float in said chamber; a passage in which said float is arranged, said passage being open at the bottom; a vent for said passage; a valve controlled by said float, said valve being arranged to affect the admission of actuating 20 fluid to said chamber and said valve being arranged to move in the direction of the pressure upon it of actuating fluid; a connecting mechanism between said valve and float arranged to utilize the pressure on the valve for 25 balancing the float. 80
105. In an apparatus for actuating liquids, the combination of a pump-chamber; an eduction-tube; a connection between the chamber and a source of actuating fluid; a 30 float in said chamber; a vent for said passage; a valve controlled by said float, said valve being arranged to effect the admission of actuating fluid to said chamber and said valve being arranged to move in the direction of 35 the pressure of actuating fluid upon it; a connecting mechanism between said valve and float arranged to utilize the pressure on the valve for balancing the float. 85
106. In an apparatus for actuating liquids, the combination of a pump-chamber; an eduction-tube; a connection with an actuating-fluid supply; a float in said chamber; a 40 passage in which said float is arranged; a vent for said chamber by way of said passage; a valve controlling said vent, said valve being arranged to be closed by said float; and means controlled by said float for opening 45 said connection. 90
107. In an apparatus for actuating liquids, the combination of a pump-chamber; an eduction-tube; means for conveying liquid through said tube by a following action through the lift of an actuating fluid; a connection with an actuating-fluid supply; a float 50 in said chamber; a passage in which said float is arranged; a vent for said chamber by way of said passage; a valve controlled by said float for opening 55 said connection. 95
108. In an apparatus for actuating liquids, the combination of a pump-chamber; an eduction-tube; a connection with an actuating-fluid supply; a float in said chamber; a passage in which said float is arranged; a vent for said chamber by way of said passage, said vent leading to the eduction-tube. 100
109. In an apparatus for actuating liquids, the combination of a pump-chamber; an eduction-tube; means for conveying liquid through the tube by a following action through the lift of an actuating fluid; a connection with an actuating-fluid supply; a float in said chamber; a passage in which said float is arranged; a vent for said chamber by way of said passage, said vent leading to the eduction-tube. 105
110. In an apparatus for actuating liquids, the combination of a pump-chamber; an eduction-tube; a connection with an actuating-fluid supply; a float in said chamber; a passage in which said float is arranged; a vent for said chamber by way of said passage, said vent leading to the eduction-tube; said eduction-tube having sufficient length between the connection with the vent and the chamber to cause a sufficient friction to reduce the pressure of liquid at the connection with the vent below the pressure of the liquid in the chamber. 110
111. In an apparatus for actuating liquids, the combination of a pump-chamber; an eduction-tube; means for conveying liquid through the tube by a following action through the lift of an actuating fluid; a connection with an actuating-fluid supply; a float in said chamber; a passage in which said float is arranged; a vent for said chamber by way of said passage, said vent leading to the eduction-tube; said eduction-tube having sufficient length between the connection with the vent and the chamber to cause a sufficient friction to reduce the pressure of liquid at the connection with the vent below the pressure of the liquid in the chamber. 115
112. In an apparatus for actuating liquids, the combination of a pump-chamber; an eduction-tube; a connection between the chamber and a source of actuating fluid; a float in said chamber; a passage in which said float is arranged, said passage being open at the bottom; vent E² leading from said passage, vent E⁴ for connecting E² and the eduction-tube; valve E arranged to close said passage and to be closed by the float; and means controlled by said float for opening said connection. 120
113. In an apparatus for actuating liquids, the combination with a pump-chamber; means for admitting liquids to said chamber; 125
- means for admitting liquids to said chamber; 130

- means for conveying liquids from said chamber; a connection between said chamber and a source of actuating-fluid supply; mechanism controlling said connection; a pressure device controlling said mechanism, said pressure device being connected with the pump-chamber and said connection being contracted relatively to the eduction-tube for the purpose described.
114. In an apparatus for actuating liquids, the combination with a pump-chamber; means for admitting liquids to said chamber; means for conveying liquids from said chamber by a following action through the lift of an actuating fluid; a connection between said chamber and a source of actuating-fluid supply; mechanism controlling said connection; a pressure device controlling said mechanism, said pressure device being connected with the pump-chamber and said connection being contracted relatively to the eduction-tube for the purpose described.
115. In an apparatus of the character described, the combination of means controllable by air-pressure for intermittently forming the liquid within the well into successive columns of great height, and valve mechanism controllable automatically by fluid-pressure for successively forcing charges of air into said successive columns of said liquid.
116. In an apparatus of the character described, the combination of mechanism for forming a body of liquid into a vertical column, means for forcing a volume of air to a point below the surface of said liquid, and mechanism controllable automatically by pressure of said liquid for suddenly releasing said volume of air within said column of liquid.
117. In an apparatus of the character described, the combination of a barrel, tubing connected therewith for raising a liquid therefrom the surface of the earth, means for causing the formation within said barrel and said tubing, of a continuous column of liquid of considerable height, means for forcing an aeriform body below the upper surface of said column, and automatic mechanism controllable by pressure of said liquid for discharging a part of said aeriform body into said column so as to lift a portion of the same to the surface of the earth.
118. In an apparatus of the character described, the combination of mechanism for accommodating a volume of liquid of a considerable height, means for forcing a volume of air below the surface of said liquid thus formed into a column, and valve mechanism controllable automatically by pressure of the liquid for releasing said air-pressure at a point below the upper level of said column of liquid for the purpose of breaking said column in two and thereby lifting the upper portion thereof to the surface of the earth.
119. In an apparatus of the character described, the combination of means for forming a body of liquid into a vertical column, valve mechanism controllable automatically by pressure of said column for directing into said column, intermediate of the ends thereof, a supply of an aeriform body, and mechanism for supplying said aeriform body under pressure so as to break said column into two parts and elevate one of said parts to the surface of the earth.
120. In an apparatus of the character described, the combination of mechanism for forming a volume of liquid into a vertical column, means for applying air-pressure to said column for the purpose of increasing the height thereof, and valve mechanism controllable automatically by the liquid-pressure of said column for the purpose of discharging a volume of air into said column of liquid.
121. In an apparatus of the character described, the combination of mechanism for forming a volume of liquid into a vertical column, means for applying air-pressure to said column for the purpose of increasing the height thereof, and valve mechanism controllable automatically by the pressure of the liquid to be raised for discharging a volume of air into said column of liquid.
122. In an apparatus of the character described, the combination of a barrel, tubing connected therewith for elevating a liquid to the surface of the earth, a chamber-valve mounted within said barrel and controllable automatically by pressure of said liquid-column for establishing communication between said tubing and said liquid-column for the purpose of breaking the latter into two parts and elevating one of said parts to the surface of the earth.
- In testimony whereof I have hereunto set my hand in the presence of two subscribing witnesses.

RUDOLPH CONRADER.
